UNITED STATES PATENT OFFICE

JOSEPH P. RUTH, JR., OF DENVER, COLORADO

DEVICE FOR CONDITIONING ORES

Application filed February 11, 1929. Serial No. 339,051.

This invention relates to improvements in conditioning devices for use in the treatment of ores.

In the process of separating the mineral values from the gangue of ore pulps, especially when flotation separation is employed, it is necessary to condition the ore before it is delivered to the flotation machines. The conditioning of the ore is effected by means 10 of chemicals with which the ore is brought into contact and with which it is kept in contact for a certain length of time. This conditioning is a continuous process and it is necessary to be able to adjust the parts so as 15 to maintain the ore in contact with the chemicals for the length of time necessary to get the best results and as this time varies for different ores, it is necessary to employ an apparatus that is provided with means by 20 which the time may be changed to fit the conditions.

The conditioning apparatus to which this invention relates, comprises a reception tank having two compartments, one of which is 25 adapted to receive the ore pulp to be treated and the other of which is adapted to receive the pulp after it has been treated. These compartments are separated by a partition provided with an adjustable weir by means 30 of which the two compartments are put into communication with each other. A large conditioning tank is placed adjacent the reception tank with its top above the top of the reception tank. Means comprising a cen- 35 trifugal pump is provided for transferring pulp from the bottom of the feed compartment to the top of the conditioning tank, and a launder is connected with the conditioning tank and has its lower end in communication 40 with the delivery compartment of the reception tank, so that any overflow from the conditioning tank will be conducted to the delivery compartment of the reception tank from which it can flow to the flotation machines 45 through a launder connected with this compartment.

A pipe is connected with the bottom of the conditioning tank and extends to the delivery compartment of the reception tank for the 50 purpose of returning the heavy parts of the

pulps to the reception tank. By means of the weir a certain proportion of the pulp which is returned from the conditioning tank is returned to the feed compartment so as to be again circulated through the conditioning tank. By adjusting this weir the proportion of the pulp to be returned can be controlled and in this manner the time that the pulp is kept in contact with the chemicals can be adjusted so as to obtain the best results. 55

Having thus briefly described the invention the same will now be described in detail and for this purpose reference will be had to the accompanying drawing in which the preferred embodiment of the invention has been illustrated and in which: 60

Fig. 1 is a plan view showing the reception and conditioning tanks and the means for transferring pulp from one to the other; 70

Fig. 2 is a vertical section taken on line 2-2, Fig. 1; and

Fig. 3 is a section through the reception tank taken on line 3-3, Fig. 1.

In the drawing numeral 1 represents a floor or foundation upon which the different parts of the device are supported and 2 represents the reception tank. This tank has been illustrated as of rectangular shape and is provided with a transverse partition 3 that separates 75 it into two compartments, A and B. Compartment A will be referred to as a feed compartment, while compartment B will be designated as the delivery compartment. The partition is provided with a weir 4, the bottom of which is formed by a gate 5 which is 80 slidable between the partition and the guides 6. This gate has an upwardly extending bar 7 which projects through a transverse beam 8 and which is perforated for the reception of a pin 9. The gate can be adjusted vertically and will be held in adjusted position by the pin. A launder 10 serves to conduct the pulp to the feed compartment and another launder 11 extends from the delivery compartment, to the flotation machines. The conditioning tank has been designated by reference numeral 12 and may be a wooden tank of stave construction. This tank is supported on some suitable supports 13 with its 95 100

bottom 14 at some distance above the level of the supporting floor. The lower part of the tank is formed by a conical portion 15 which terminates in an opening 16. Secured in the opening 16 is a cross 17 to one opening of which a pipe 18 is connected. This pipe extends to a source of water under high pressure and is provided with a control valve 19. To the opposite opening a pipe 20 is connected. This pipe extends to the delivery compartment of the reception tank and is provided with a valve 21 which controls the flow of pulp through this pipe. The bottom opening of the cross is provided with a removable plug 22 for use in draining the tank. Pipe 20 is provided with a T 23 to which the pipe 24 is connected. A valve 25 controls the flow through pipe 24. A centrifugal pump 26 has its intake port connected with the lower end of compartment A by means of a pipe 27 and a pipe 28 extends from the outlet port of the pump to the top of the conditioning tank. The centrifugal pump may be of any well known make and is preferably operated by means of an electric motor 29. A launder 30 has its upper end connected with the upper end of the conditioning tank at 31 and has its lower end in communication with the delivery compartment B. The delivery compartment is preferably provided with a diagonal partition 32 with which the partition 33 connects in the manner shown in Fig. 3, so as to produce a shallow compartment of rather small capacity.

Let us now assume that pulp is delivered to the feed compartment A through the launder 10 and that the centrifugal pump is in operation. This pulp will be transferred from the feed compartment to the conditioning tank in which are located the chemicals by means of which the treatment is effected. When the level of the pulp in the conditioning tank reaches the line 34 it will start overflowing through the launder 30 into the delivery compartment B. As compartment B fills up, some of the pulp will flow through the weir back into the feed compartment, while the remaining part of the pulp will flow through the launder 11 to the flotation machine. By opening valve 21, a portion of the pulp from the conditioning tank will be returned to the delivery compartment through pipe 20. It is evident that when the pulp is delivered to the conditioning tank through pipe 28, that it will cause a considerable amount of agitation which will tend to maintain the smaller particles in suspension, and these will therefore return to the reception tank by way of launder 30. The heavier particles will settle to the bottom of the tank and will be returned through pipe 20. In order to facilitate the flow of the heavy pulp from the bottom of the conditioning tank, valve 19 may be opened which permits a stream of water under high pres-

sure to enter from pipe 18 and to produce what may be termed an injector action which facilitates the flow of the pulp. The level of gate 5 is adjusted as above explained so as to return the desired proportion of the pulp to the feed compartment from which it will be mixed with the pulp from launder 10 and subjected to another treatment in the conditioning tank, in this manner the length of the treatment can be conveniently controlled. 75

When the conditioning tank is to be drained, valve 25 is opened which permits the material to drain outwardly through pipe 24. If the material in the tank is caked or so thick that it will not readily flow, valve 21 may be closed and valve 19 opened, whereby high pressure water will be forced into the tank from below and agitate the pulp and mix it with water to such an extent that it will flow through the outlets provided therefor. 85

From the above description it will be seen that I have produced a conditioning device of a simple construction by means of which ore pulp can be quickly and cheaply conditioned and which is provided with means for varying the length of time the pulp is kept in contact with the chemicals so that adjustments can be readily made to obtain the best results under the different conditions met with in actual practice. 90 95

Having described the invention what is claimed as new is:

1. A conditioning device comprising, in combination, a reception tank divided into two compartments by means of a transverse partition, means for delivering ore pulp to one of the said compartments, a conditioning tank, means for transferring pulp from the bottom of the reception compartment to the top of the conditioning tank, means for transferring pulp from the bottom of the conditioning tank to the other compartment of the reception tank, means for conducting overflow from the top of the conditioning tank to the last named compartment, a weir in the wall between the two compartments of the reception tank and means for adjusting the height of the weir and an overflow from the second named compartment. 100 105 110 115

2. A conditioning device comprising, in combination, a reception tank divided into two compartments by means of a transverse partition, one of said compartments being adapted to receive the pulp to be treated, the other compartment being adapted to receive the treated pulp, a conditioning tank, means for transferring the pulp from the first mentioned compartment to the conditioning tank, a pipe connecting the bottom of the conditioning tank with the second named compartment, a launder extending from near the top of the conditioning tank to the second named compartment and an adjustable 120 125 130

weir in the partition between the two compartments.

3. A conditioning device for the treatment of ores comprising, in combination, a reception tank having a feed compartment adapted to receive the pulp to be treated and a delivery compartment adapted to receive the treated pulp, said compartments being separated by a partition provided with an adjustable weir; a conditioning tank whose top is at a higher level than that of the reception tank, a launder extending from the top of the conditioning tank to the delivery compartment of the reception tank, a discharge launder connected with the delivery compartment, means for transferring pulp from the bottom of the feed compartment to the conditioning tank and means for conducting pulp from the bottom of the conditioning tank to the delivery compartment.

4. A conditioning device for the treatment of ores comprising, in combination, a reception tank having a feed compartment adapted to receive the pulp to be treated and a delivery compartment adapted to receive the treated pulp, said compartments being separated by a partition provided with an adjustable weir, a conditioning tank whose top is at a higher level than that of the reception tank, a launder extending from the top of the conditioning tank to the delivery compartment of the reception tank, a discharge launder connected with the delivery compartment, means for transferring pulp from the bottom of the feed compartment to the conditioning tank, means for conducting pulp from the bottom of the conditioning tank to the delivery compartment and means for introducing water under pressure into the bottom of the conditioning tank.

5. A conditioning device comprising, in combination, a reception tank, a conditioning tank, means for delivering pulp to the reception tank, means for transferring the pulp from the reception tank to the conditioning tank, means for returning the pulp to the reception tank and means for separating the returned pulp into two streams, and for returning one of said streams to the conditioning tank.

In testimony whereof I affix my signature.
JOSEPH P. RUTH, JR.
